(57) **CLAIM**

We claim the ornamental design for a handle for shopping cart, as shown and described.

DESCRIPTION

FIG. 1 is a perspective view of a handle of a shopping cart showing our new design.

FIG. 2 is a front view of the handle shown in FIG. 1.

FIG. 3 is a back view of the handle shown in FIG. 1.

FIG. 4 is a right side view of the handle shown in FIG. 1.

FIG. 5 is a left side view of the handle shown in FIG. 1; and, FIG. 6 is a top view of the handle shown in FIG. 1.

The bottom view is not a part of the claimed design.

The broken lines shown in the figure are included for the purpose of illustrating portions of the handle for a shopping cart and form no part of the claimed design.
